UNITED STATES PATENT OFFICE.

CHRISTOPHER M. STURGIS, OF KANSAS CITY, KANSAS.

RAILROAD TIE.

Application filed August 12, 1921. Serial No. 431,663.

To all whom it may concern:

Be it known that I, CHRISTOPHER M. STURGIS, a citizen of the United States, residing at Kansas City, in the county of Wyandotte and State of Kansas, have invented certain new and useful Improvements in Railroad Ties; and I do declare the following to be a full, clear, and exact description of the invention, such as will enable others skilled in the art to which it appertains to make and use the same, reference being had to the accompanying drawings, and to the figures of reference marked thereon, which form a part of this specification.

This invention relates to improvements in railroad ties and more particularly to reinforced concrete ties wherein new and improved structural features are combined to support the usual steel rails on the road bed, it being one of the principal objects of the invention to provide means for supplying the necessary flexibility in a railroad track and strengthening the foundation and anchorage of the track on the road bed.

Another object of the invention resides in the manner in which I form and place the reinforcing members so that the tie is not only reinforced throughout its rigid section but is flexibly tied together at an intermediate point.

Still another object of the invention is to provide a durable mounting for the track bolts whereby they may be inserted and removed a number of times without injury to the apertures in the tie and whereby the apertures are especially reinforced for local strains incident to drawing the track bolts down very tightly.

It is another object of the invention to construct a tie which may be tamped with greater ease and more securely than those of ordinary construction.

With these and other objects in view I have provided the improved details of structure which will hereinafter be more fully described and illustrated in the accompanying drawings, wherein:

Fig. 1 is a perspective view of a portion of a railroad track illustrating the use of my improved railroad tie.

Fig. 2 is a transverse section through the track showing particularly the manner of placing and joining the reinforcing.

Fig. 3 is a detail perspective view of one of the tie sections, a fragment being broken away to show the reinforcing.

Fig. 4 is a detail sectional view on a slightly enlarged scale, illustrating the manner of applying the track bolts.

Referring more in detail to the parts:

1 and 2 designate independent sections of my improved tie which are identical in size, shape and construction and each section comprises a longitudinal portion 3 having a heavy rib 4 extending along the base so as to provide shoulders 5 and 6 at each side, under which loose rock may be tamped. The upper face of the portion 3 has a groove 7 extending the full length of the section and adapted to register with similar grooves of adjoining sections and receive a rectangular strip 8 of creosoted wood or other water-proofed, resilient material whereby the tie sections are not only held in alignment but a resilient, sound-deadening base provided for the rails 9, which may be clamped to the tie and strip by any suitable device, such as, for example, the clamps 10 and ordinary track bolts 11, it being understood that while I have shown two bolts to a tie section that I do not limit myself to this number as it is evident that it may be necessary under certain conditions of track construction to have four or even six bolts to a section.

Extending at right angles from each side of the portion 3 and integral therewith are transverse portions 12 and 13, which are in alignment and having a bearing rib 14 merging with the rib 4 of the longitudinal section and formed so as to provide side shoulders 15 and 16 and an end shoulder 17, beneath which track ballast, such as loose rock, can be tamped to support the ties.

Reinforcing rods 18 are placed near the base of the portion 3 having turned-up ends 19 provided with anchor hooks 20 whereby any downward flexing of the portion 3 in the center places the rods in tension.

Another series of reinforcing rods 21 are placed in the transverse portions 12 and 13 and extend from one end to the other and beneath the longitudinal portion 3. These rods consist of a loop 22 projecting from a notched recess 23 of the portion 13 and parallel portions 24 and 25 bent downwardly to a point adjacent the rods 18 and then angle upwardly to near the end of the tie. The rod 25 has an anchor hook 26 to secure the end so that any stress exerted by a train passing over the track places the rod in tension.

The loops 22 are positioned so that when the sections 1 and 2 are placed together, the loops will register to receive a wedge bar 27 which extends through all the loops and has 5 a series of apertures 28 into which pins 29 may be inserted to prevent the wedge from coming out in either direction. A dowel 30 of hard wood or like material is inserted in apertures 31 in the ends of the ribs 14 to 10 keep the parts in alignment.

Another reinforcement 32 consisting of two or more layers of rods, wire mesh, expanded metal or the like, extends horizontally throughout the entire tie and supplies 15 additional reinforcement to the overhanging parts.

The particular method of applying the track bolt which I wish to use consists of casting a flat coiled wire 33 around the inner 20 face of the hole 34 and letting the wire project into the hole to provide threads 35 into which the threads on the track bolt may grip and also casting a second wire 36 of slightly larger diameter around the first, so 25 that any local strains caused by tightening the bolt too tight will be resisted by the second wire and prevent the concrete from cracking.

In placing the ties, the road bed is prepared in the usual manner and the tie sections 30 set in place and locked by the wedge 27. The lining strips 8 are then placed in the grooves 7 and the steel rails bolted on the strips by means of the track bolts. If the 35 rails do not set to the proper gauge, the wedge may be moved back and forth to permit a spread or contraction of the rails and when set, the pins 29 are placed to hold the parts in position. The ballast is then tamped 40 in so as to fill closely around and under the ribs 4 and 14 and beneath the shoulders 5, 6, 15 and 16, thereby presenting a wide area 45 for the substantial support of the track.

It is apparent that when the tie is in place, 45 any transverse or longitudinal movement thereof is resisted by the ballast against the longitudinal and transverse ribs.

The tie is particularly applicable for banking around curves as the rail on the outer 50 radius of the curve can be raised and rock tamped therebeneath without in any way affecting the strength of the tie.

What I claim and desire to secure by Letters-Patent is:

55 1. A reinforced concrete tie comprising like sections, reinforcing rods extending through each of said sections, loops on said rods projecting from mating ends of said sections, and a wedge for joining the loops 60 and connecting the sections together.

2. A reinforced concrete tie comprising like sections, reinforcing rods extending through and anchored in each of said sections, rectangular loops on said rods projecting from mating ends of said sections, a 65 wedge for said loops, and pins for preventing displacement of said wedge.

3. A reinforced concrete tie comprising like sections flexibly connected together, and a dowel for holding said sections in alignment. 70

4. A reinforced concrete tie comprising like sections flexibly connected together, a dowel for holding the mating ends of said sections in alignment, and strips for holding 75 adjacent ties in alignment.

5. A reinforced concrete tie comprising body portions for lying transversely of a track and integral members extending from the sides of the body portions for lying longitudinally with the track, there being 80 grooves extending continuously through the upper faces of the longitudinal members and the intermediate body portions and ribs extending downwardly from the longitudinal 85 members and body portions, beneath said grooves, and resilient strips in said grooves extending beyond the ends of the longitudinal members to seat in the grooves in adjacent ties to form continuous rail seats. 90

6. In a reinforced concrete tie, a tie section comprising a longitudinal portion having a top groove and a base rib, a transverse portion extending from each side of said longitudinal portion and having a base rib 95 crossing said first rib, and reinforcing rods extending through said longitudinal and transverse portions.

7. A monolithic tie section comprising longitudinal and transverse portions formed 100 into a cross, base ribs extending along each portion so as to provide shoulders, trussed reinforcing rods passing through each portion, mesh reinforcing passing through the entire section, and means for supporting a 105 rail on said section.

8. In a reinforced concrete tie, paired body portions for lying transversely of a track and each comprising longitudinal members for supporting a rail, the inner end of each body portion having an upwardly facing shelf, reinforcing members in each body portion having loops extending over the respective shelves and registering with like loops on reinforcing members projecting from the 110 opposite body portion, and a connector extending through the registering loops. 115

In testimony whereof I affix my signature.

CHRISTOPHER M. STURGIS.
